UNITED STATES PATENT OFFICE.

ALFRED HARRINGTON, OF LEICESTER, ENGLAND, ASSIGNOR TO UNITED SHOE MACHINERY CORPORATION, OF PATERSON, NEW JERSEY, A CORPORATION OF NEW JERSEY.

SOLE-EDGE-TREATING TOOL.

Application filed September 6, 1921. Serial No. 498,851.

To all whom it may concern:

Be it known that I, ALFRED HARRINGTON, a subject of the King of England, residing at Leicester, Leicestershire, England, have 5 invented certain Improvements in Sole-Edge-Treating Tools, of which the following description, in connection with the accompanying drawings, is a specification, like reference characters on the drawings indicating 10 like parts in the several figures.

This invention relates to edge setting machines and is illustrated as embodied in a machine of the type set forth in United States Letters Patent No. 1,078,684, granted 15 November 18, 1913 on application of F. B. Keall, J. Gouldbourn and A. E. Jerram in which an iron for setting the sole edge is moved along the length of the sole edge and in which an indenting wheel is mounted near 20 the edge setting iron so that when the edge of the sole is pressed against the iron, the upper surface of the welt or sole is pressed against the under surface of the indenting wheel.

It is desirable that provision be made in 25 machines of the type above referred to for insuring that differences in thickness of different parts of a given shoe sole, as well as differences in thickness of different shoe soles, may be fully compensated for to the 30 end that the pressure of the indenting wheel may be substantially uniform whatever the thickness of any given sole at any point. It is also important that in providing for such relative adjustment of the wheel and iron 35 heightwise of the shoe, there will be no substantial interference with the desired continuity of the working surfaces of the tools at the upper corner of the sole edge.

In view of these considerations, it is an object of the present invention to provide an 40 improved edge of setting machine of the type above referred to, by the use of which the simultaneous performance of edge setting and indenting operations may be still further 45 facilitated by the provision of a relative heightwise movement of the edge setting iron and indenting wheel such that the wheel will follow, with substantially uniform pressure, variations in sole thickness or in the 50 vertical contour of the upper side of the sole or welt edge.

In accordance with a feature of the present invention, this problem is solved by providing for movement of the indenting wheel 55 heightwise of the shoe in response to varia-

tions in sole thickness, the indenting wheel being undercut and a part of the operative surface of the edge setting iron being arranged to extend into the undercut portion of the wheel, so that heightwise movement 60 of the wheel will not interfere with the continuity of the working surfaces of the tools at the upper corner of the sole edge.

This and other features of the invention, comprising various combinations and arrangements of parts, will be understood from the following description of two embodiments of the invention, selected for purposes of illustration and shown in Figs. 1 and 2 of the accompanying drawing respectively. The figures are both side elevations partly broken away, of an edge treating implement comprising an iron and indenting wheel.

The drawings illustrate a preferred embodiment of the invention in its application to a machine having the general organization set forth in detail in United States Letters Patent No. 1,078,684, above referred to, to which patent reference may be had for a 80 more detailed disclosure of parts not herein specifically set forth.

In Fig. 1 is illustrated an edge setting iron 10 of the type illustrated in said Letters Patent and shown more in detail in United States Letters Patent No. 1,161,868, granted November 30, 1915, on application of F. B. Keall (except for a difference in profile to adapt it for a different style of work). This iron 10 is adjustably fixed to a holder 12 by 90 means of the screw 14. The holder 12 is mounted in the machine and oscillated perpendicularly to the plane of the drawing in any desired way. At the upper part of the holder at 16 is pivoted a bell-crank 18 against one arm of which bears a spring-pressed plunger 20, and upon the other arm of which is rotatably mounted the indenting wheel 22 on the screw 24. In Fig. 1 the wheel is somewhat undercut, as at 26, and overlaps 95 the upper bevel forming lip 28 of the iron which extends into said undercut portion of the wheel. This allows the wheel to have an adequate range of movement heightwise of the iron without materially disturbing 100 their horizontal operative relationship or the continuity of their operating surfaces at the junction of the edge face of the sole with the upper face of the sole or welt. The entire lateral surface of the sole edge and the up- 105 110

per surface of the sole or welt are thus completely finished right out to their junction. The bell-crank and wheel have free pivotal motion about the pivot 16, the wheel being forced against the work 29 by the spring plunger 20, the whole tool being adjusted with sufficient play to accommodate the extremes of sole thickness which will be presented to it. A screw 30 limits the movement of the wheel away from the iron.

Fig. 2 illustrates a construction adapted for use with a double hump iron. The general problem of the double hump iron and indenting wheel combination is discussed in United States Letters Patent No. 1,276,027, granted Aug. 20, 1918, on the application of Keall, Harrington and Bassett, and need not be more specifically treated herein.

In Fig. 2 the wheel 22' is seated in a depression between the humps 10' of the iron and is mounted on a bell-crank 18' pivoted at 16'. All other parts are numbered similarly to the corresponding parts in Fig. 1.

Having described my invention, what I claim as new and desire to secure by Letters Patent of the United States is:—

1. An edge setting and indenting device comprising a holder, an edge setting iron secured to the holder and having an operative surface to treat the lateral edge of a shoe sole, an indenting tool for treating the upper face of the sole, and a yieldable mounting for said indenting tool to allow movement of the indenting tool heightwise of the work in a direction substantially perpendicular to the operative portion of its surface under pressure of said work against the operative surface of said indenting tool said indenting tool having its operative surface extending to and meeting the operative surface of the edge iron in all positions to insure a continuous finishing surface as the indenting tool rides over a sole of uneven thickness.

2. An edge setting and indenting device comprising a holder, an edge setting iron secured to the holder and having an upper bevel forming lip, an indenting tool having an operative surface intersecting the surface of said lip and extending along the upper face of a shoe sole, and a pivotal mounting for said indenting tool construct-

ed and arranged to allow it to move heightwise of the work in a direction substantially parallel to the face of the edge setting iron and to maintain a close junction of said finishing surfaces so as to treat the upper surface of the sole all the way out to the edge.

3. An edge setting and wheeling device comprising a holder, an edge setting iron secured to the holder and having an operative surface for burnishing the lateral edge of a shoe sole, an indenting wheel having an operative surface extending along the upper face of the sole edge and meeting the operative surface of the edge iron, and a pivotal mounting for the wheel constructed and arranged to allow the work to move the wheel heightwise of the sole when the sole edge is of uneven thickness in a direction substantially parallel to the face of the edge iron and to maintain the continuity of said surfaces.

4. An edge setting and wheeling device comprising an iron having an upper bevel forming lip, and an undercut indenting wheel, said lip extending into the undercut portion of the wheel, the wheel being mounted for operative movement heightwise of the iron to follow a vertically uneven sole edge and co-operating with said lip to form a substantially continuous sole edge finishing surface.

5. An edge setting and indenting device comprising a holder, an edge setting iron secured to the holder and having an operative surface arranged to treat the vertical edge of a shoe sole, and an indenting tool also secured to the holder and arranged to treat the upper sole or welt face, said edge setting iron and said indenting tool being constructed and arranged so that their respective fields of operation extend to the corner formed by the intersection of the vertical edge of the sole and the upper sole or welt surface and being mounted to provide for relative movement of said iron and tool heightwise of a sole to permit the device to accommodate itself automatically to variations in sole thickness.

In testimony whereof I have signed my name to this specification.

ALFRED HARRINGTON.
